UNITED STATES PATENT OFFICE.

RUDOLF SINKWITZ, OF PIRNA, GERMANY.

METHOD AND APPARATUS FOR TWISTING, REELING, AND WASHING FRESHLY SPUN
AND SPOOLED ARTIFICIAL-SILK THREAD.

Application filed November 10, 1923. Serial No. 673,902.

To all whom it may concern:

Be it known that I, RUDOLF SINKWITZ, a citizen of the German Republic, and a resident of Pirna, Saxony, Germany, have invented certain new and useful Improvements in methods and apparatus for twisting, reeling, and washing freshly spun and spooled artificial silk thread, of which the following is a specification.

10 This invention relates to a method and apparatus for twisting, reeling and washing freshly spun and spooled artificial silk.

According to the method of the present invention the artificial silk which has been 15 spooled from the precipitation bath upon a twisting spool is pulled off from this spool, placed on a twisting spindle, without previous treatment, i. e., in an acid condition and reeled directly upon a reeling device dipping and rotating in a water bath.

The immediate reeling of artificial threads from the twisting spools has not been hitherto possible on account of the weakness of the thread which has not been freed of the 25 impurities from the precipitation process. The resistance of the spinning spool in its still acid condition against untwisting is increased by the quick rotation of the spool necessary for the twisting, by which the 30 moisture contained in the spool is thrown off by centrifugal action and by the crystallizing out of the salts adhering to the thread. This prevents an easy liberation of the thread from the spool, reduces the 35 tensile and breaking strength of the threads and is the cause of the prevention of an entire emptying of the spool, thus causing a considerable amount of untwisted threads to remain thereon.

40 According to the invention the resistance of the acid thread spool is balanced by a continuous moistening of the twisting spool during its rotation. Thus the crystallizing out of the salts is prevented and an easy 45 separation of the threads from the spool made possible; furthermore a certain lixiviation is achieved and the tensile and breaking strength is quite apart from the thickening by twisting of the thread, so much increased that the thread, after the twisting 50 operation, may immediately and directly be reeled without the necessity of inserting a washing conduit between the twisting device and the reeling device and its further 55 treatment i. e. the complete washing and

purifying, bleaching and drying, may be carried out in the reeled condition of the thread.

The method is advantageously carried 60 into effect in such a manner that the said thread-spool, placed upon the twisting spindle is caused to rotate in atomized liquid in order to achieve a particularly effective moistening of the spool and of the pulled-off thread.

65 For carrying the method according to the invention into effect, a twisting machine combined with a reeling device is used, in which a moistening device, for example a liquid atomizer, is arranged in such a manner that the twisting spool is moistened during its rotation, for example, by rotating in the atomized liquid.

An apparatus for carrying into effect the 70 method according to the invention is illustrated diagrammatically and by way of example in the annexed drawings, in which

75 Figs. 1 and 2 show an apparatus for twisting, reeling and washing spooled artificial silk, in cross section and side elevation respectively. (Fig. 2 is a part section on the line A—B of Fig. 1.)

Journalled in a frame *a* are twisting spindles *d* carrying twisting spools *b*. Each 80 twisting spool rotates within a container *e*.

85 Arranged above each twisting spool is a thread guide *k* and a pulling off roller *m* by means of which the thread is led, with very little tension, to a reeling device *t*. The twisted threads are guided over glass rods *u*. The reeling device *t* dips and rotates partially in a bath *w* arranged on both 90 sides of the apparatus and along its entire length.

95 In each of the containers *e* of the twisting spools terminates, at about the middle of the spool, a water pipe *f* provided at its end with an atomizer *g*.

The atomizer *g* preferably consists of two nozzles arranged at an adjustable angle, in 100 such a manner that two water jets impact one upon the other, thus causing a specially effective atomizing of the water, in the form of a spreadout fan, moistening the twisting spool and the thread.

105 The effective washing by moistening the thread during twisting is to be explained by the fact that the atomized water comes into good contact with the thread, because during the twisting process each portion of 110

the thread is exposed to the intimate action of the spray-jet for a certain time, and furthermore, each layer of the twisting spool becoming free during the twisting process, 5 is exposed for some time to the action of the atomized liquid. There is no difficulty in making the washing combined with the moistening of the twisting spool, so effective, by means of a specially effective atomizing device that the thread solely by this moistening, receives sufficient strength to be immediately and directly reeled and to undergo the further lixiviation on the reeling device, rotating in a waterbath. 10 15 The thread thus washed and twisted is brought directly without the necessity of being led through washing conduits hitherto used to the reeling devices, rotating in waterbaths, so that the thread, during its reeling, is further washed. 20 The feature of the invention does not only consist in the washing of the strands of reeled up artificial silk whilst upon the reeling device, but also in the combination of 25 the twisting during moistening, which has a double effect, with the immediately following reeling of the thread; the reeling device for the purpose of a final washing of thread rotating in a washing-bath. The double effect of moistening the thread upon the twisting spool and for a further period after becoming free of the latter consists therein that the spool may be used to the last thread thereon, since the drying out of the thread 30 35 by shaking is prevented and at the same time the thread is already out and freed of acids by which the directly following reeling and washing in the reeled condition becomes possible. 40 Having now particularly described and ascertained the nature of my said invention what I claim as new is:—

1. A method for twisting, reeling and washing freshly spun and spooled artificial silk, according to which the unpurified threads on a twisting spool carried by a

twisting spindle are pulled off from the spool whilst the latter is rotated and moistened, said threads being subsequently directly reeled without intermediate treatment, washed and further treated in the reeled condition. 50

2. A method as claimed in claim 1, according to which the spinning and twisting spool is rotated in atomized liquid. 55

3. Apparatus for carrying into effect the method claimed in claim 1, characterized by the provision of a moistening device for moistening the rotating twisting spool upon the twisting spindle during the twisting 60 operation.

4. A machine of the class described, comprising, a twisting spindle, means for washing and moistening the unpurified threads as they are being drawn off therefrom, a reeling device for winding the threads drawn off from the twisting spindle, and means for washing the threads on the reeling device during movement of the latter. 65

5. A machine as claimed in claim 4, 70 wherein said last-named washing means include a bath in which the reeling device partially rotates to intermittently dip portions of the threads thereon.

6. The method of treating unpurified, 75 spooled artificial silk, consisting in moistening and washing the thread simultaneously with the drawing off and twisting thereof, and then reeling the thread so twisted and further washing the same. 80

7. The method of treating unpurified, spooled, artificial silk, consisting in moistening the thread on the spool immediately before or with the drawing off of the same, simultaneously twisting the thread as drawn off the spool, reeling the twisted thread, and then giving the reeled thread successive washings in a bath. 85

Signed at Dresden this 22nd day of October 1923.

RUDOLF SINKWITZ.
